UNITED STATES PATENT OFFICE.

RUDOLPH KASINSKI, OF NEW YORK, ASSIGNOR TO THE NORTH AMERICAN IRON WORKS, OF BROOKLYN, N. Y.

DESIGN FOR A STATUE.

SPECIFICATION forming part of Design No. 11,984, dated October 26, 1880.

Application filed August 19, 1880. Term of patent 14 years.

To all whom it may concern:

Be it known that I, RUDOLPH KASINSKI, of the city and State of New York, have invented a Design for a Statue, of which the following 5 is a specification.

This design for a statue is adapted to being cast in metal and used as an ornament, either alone or in connection with a fountain.

The said design is represented in the accompanying photographs, in which said statue is shown from two different points.

The design represents a sea-lion with the head bent back and a female figure resting upon the sea-lion, with one arm across the animal's neck and the other distended upwardly 15

and carrying a feather. Loose drapery is represented as over portions of the female figure, and there is a base upon which the representation of the sea-lion rests.

I claim as my invention—

The design for a statue composed of the representation of a sea-lion and a female figure, as described and shown.

Signed by me this 2d day of June, A. D. 1880.

RUDOLPH KASINSKI.
